TRAFFIC PROTECTION APPARATUS

Frank H. Nicholson, Penn Township, Allegheny County, Pa., assignor to The Union Switch & Signal Company, Swissvale, Pa., a corporation of Pennsylvania

Application April 25, 1946, Serial No. 664,780

4 Claims. (Cl. 246—219)

1

My invention relates to traffic protection apparatus, and particularly to apparatus for providing crossover protection for trains moving along railway tracks which are connected with each other by a crossover track through hand operated track switches.

A requisite for crossover protection apparatus is that it must be so arranged that a car or locomotive, while occupying a crossover such for example as a crossover connecting two main tracks, while the switches are in the normal position for train movements along the main tracks, will cause a signal for each main track to indicate stop if the car or locomotive is within fouling distance of that main track. In crossover protection schemes embodying track circuits, one characteristic should therefore be high shunting sensitivity in order to insure that the crossover track circuit will be shunted if the crossover track has high contact resistance due to infrequent train movements over the crossover.

One feature of my invention is the provision of two coded crossover track circuits, which inherently have higher shunting sensitivity than non-coded track circuits having the same normal battery voltage. These track circuits are also so arranged as to provide protection against defective insulated rail joints.

A further feature of my invention is an arrangement of decoding circuits such that the two track relays require only one decoding transformer and one code detecting relay.

I shall describe two forms of apparatus embodying my invention, and shall then point out the novel features thereof in claims.

In the accompanying drawings, Fig. 1 is a diagrammatic view showing one form of apparatus embodying my invention, in which the polarity of the current supplied to the crossover track circuits is periodically reversed at a given code rate; and Fig. 2 is a diagrammatic view showing a modified form of the apparatus of Fig. 1, in which the polarity of the current supplied to the crossover track circuits is not reversed, but the current is periodically interrupted at a given code rate.

Similar reference characters refer to similar parts in each of the views.

Referring first to Fig. 1, a stretch of railway is shown comprising two parallel tracks, designated by the reference characters 1T and 2T, connected with each other by a crossover track, designated 3T, through hand operated switches 1W and 2W. Track 3T is divided, by means of insulated joints 4, into two sections a—b and b—c.

2

Each of the sections a—b and b—c is provided with a track circuit including a suitable source of current, such as a battery 1Q or 2Q respectively, connected through a variable resistor 5 and pole changing contacts 6 and 10 of a coding device 180CT across the rails 3a and 3b of track 3T adjacent the end of its section at the mid point b of track 3T. Coding device 180CT is constantly energized by a suitable source of current having terminals B and N, and therefore contacts 6 and 10 of this device are repeatedly moved to connect alternately with their front and back points. Each of these track circuits also includes a polar stick code following track relay 1R or 2R respectively, connected through a variable resistor 8 and switch contacts 7 and 9 operated by switch 1W or 2W respectively, across the rails adjacent the opposite end of its section.

A polar contact 11 is operated by relay 1R for controlling current for repeatedly reversibly energizing the primary winding of a decoding transformer F. A condenser D is connected across the normal and reverse points of contact 11 to serve as an arc suppressor. A polar contact 14 is operated by relay 2R, and mechanically rectifies the current output from the secondary winding of transformer F for energizing a slow pick-up and slow release code detecting relay RP.

Signal control circuits for tracks 1T and 2T are controlled by contacts 17 and 18, respectively, of relay RP.

Referring now to Fig. 2, the apparatus, here shown, differs from that of Fig. 1 in that current, instead of being supplied to the track circuits through pole changing contacts, is controlled by contacts 19 of coding device CT, which periodically interrupts the current and place shunts across the rails of the track sections; code following relays 1R and 2R are neutral relays; and, in order to simplify the drawing, resistor 8 and switch contacts 7 and 9 are omitted.

Having thus described, in general, the arrangement of the apparatus I shall now describe, in detail, its operation.

As shown in the drawings, all parts are in the normal condition, that is, contacts 6 and 10 of coding device 180CT shown in Fig. 1, and contacts 19 of coding device CT shown in Fig. 2, are being repeatedly closed alternately at their front and back points at a suitable frequency such, for example, as 180 cycles per minute; switches 1W and 2W are in the normal position as shown in the drawings, and hence relays 1R and 2R in Fig. 1 are being energized by current of alternately normal and reverse polarity at a frequency

corresponding to that of the coded current being supplied to the track circuits; relays 1R and 2R in Fig. 2 are being successively energized and de-energized at the code frequency; and relay RP is energized by current controlled by contacts of relays 1R and 2R.

Each time the contacts 6 and 10 of coding device 180CT are closed at their front points, relay 1R is energized by current of normal polarity in a circuit passing from the positive terminal of battery 1Q, through a variable resistor 5, front point of contact 6, rail 3a, contact 7 of switch 1W closed in the normal position, variable resistor 8, winding of relay 1R, contact 9 of switch 1W closed in the normal position, rail 3b, and the front point of contact 10 back to the negative terminal of battery 1Q. Each time the contacts 6 and 10 are closed at their back points, relay 1R is energized by current of reverse polarity in a circuit which is the same as the normal circuit just traced except that it includes the back points instead of the front points of contacts 6 and 10.

Relay 2R is controlled by contacts of coding device 180CT which are closed at their front and back points at the same times as the contacts of coding device 180CT which control relay 1R. Relay 2R is therefore energized by current of normal and reverse polarities simultaneously with relay 1R.

Each time that contact 11 of relay 1R becomes closed in the left-hand position, as shown in the drawings, a current pulse is supplied from positive terminal B of a suitable source of current, to contact 11, through portion 12 of the primary winding of transformer F, to negative terminal N of the same source of current. Each time that contact 11 becomes closed in the right-hand position, a current pulse is supplied by a similar circuit, but in the opposite direction through portion 13 of the primary winding of transformer F.

Since relays 1R and 2R are simultaneously energized by current of like polarities, contact 14 of relay 2R becomes closed in the left-hand position at the same time that contact 11 of relay 1R becomes closed in the left-hand position, and similarly these contacts become simultaneously closed in their right-hand positions. Contact 14, connected in the circuit arrangement shown, therefore serves to rectify the current output from the secondary winding 15-16 of transformer F for energizing the code detecting relay RP.

Contacts 17 and 18 of relay RP are therefore closed in the signal circuits for tracks 1T and 2T, respectively.

If switch 1W should be reversed for a train movement over the crossover track 3T, or if section a-b should be shunted by a train, relay 1R would become deenergized, and would therefore cease to move its contact 11 between the right and left-hand positions. One of the portions 12 and 13 of the primary winding of transformer F would therefore remain deenergized, and the other portion could only be energized by steady direct current. The secondary winding of transformer F would therefore be deenergized, and relay RP would also be deenergized and its contacts 17 and 18 would open the signal control circuits, causing signals for both tracks 1T and 2T to indicate stop.

If switch 2W should be reversed for a train movement over crossover track 3T, or if section b-c should be shunted by a train, relay 2R would become deenergized, and would therefore cease to move its contact 14 between the left and right-hand positions. Contact 14 would therefore cease

to rectify the secondary current output from transformer F, and hence contacts 17 and 18 of relay RP would again open the signal control circuits.

In the arrangement shown in Fig. 2, when the contacts of coding device CT are closed at their front points, relay 1R becomes energized by a circuit passing from the positive terminal of battery 1Q, through a variable resistor 5, front point of a contact 19 of coding device CT, rail 3a, winding of relay 1R, and rail 3b back to the negative terminal of battery 1Q. When the contacts of coding device CT open at their front points, battery 1Q is disconnected from section a-b, and when these contacts become closed at their back points, a shunt is placed across rails 3a and 3b, and hence relay 1R becomes deenergized. Relay 2R is controlled similarly to relay 1R. Since relays 1R and 2R are controlled by contacts of the same coding device CT, contacts 20 and 21 of these relays will be simultaneously closed at their front points, and also simultaneously closed at their back points.

Transformer F and relay RP of Fig. 2 are controlled by contacts 20 and 21 similarly to the manner in which transformer F and relay RP are controlled in Fig. 1.

Some of the advantages provided by apparatus embodying my invention are as follows:

1. *Fouling protection.*—A train occupying crossover track 3T at any point within fouling distance of either track 1T or 2T will deenergize either relay 1R or 2R, which will in turn deenergize relay RP and thereby open the signal control circuits for both tracks 1T and 2T.

2. *Superior shunting sensitivity.*—As has already been stated, coded track circuits inherently have higher shunting sensitivity than non-coded track circuits having the same normal battery voltage.

3. *Broken rail protection.*—All portions of the track rails in crossover track sections a-b and b-c are included in the track circuits in series, and hence the best possible broken rail protection is provided.

4. *Foreign current protection.*—A well-recognized feature of coded track circuits is their immunity to foreign currents.

5. *Protection against defective insulated joints.*—If the insulated joint at a in rail 3a should break down, the track circuit, not shown, for track 1T would be deenergized. If the insulated joint at a in rail 3b should break down, track relay 1R would be shunted. If the insulated joint in rail 3b at point b should break down, and if there should be a current leak from rail 3a of section b-c to rail 1a of track 1T, tending to place batteries 1Q and 2Q in series across the rails of track 1T, the successive reversal of polarities of the current supplied to rails 3a and 3b would prevent operation of a track relay of track 1T by batteries 1Q and 2Q. Similarly, if the insulated joint in rail 3a at point b should break down, the successive reversal of polarities of the current supplied to rails 3a and 3b would prevent operation of a track relay of track 2T by batteries 1Q and 2Q. If the coding device 180CT should fail to reverse the polarity of the current supplied to the track circuits, relays 1R and 2R would cease to move contacts 11 and 14 between the left and right-hand positions, and hence relay RP would be deenergized and cause the signals for tracks 1T and 2T to indicate stop.

Although I have herein shown and described only two forms of apparatus embodying my in-

vention, it is understood that various changes and modifications may be made therein within the scope of the appended claims without departing from the spirit and scope of my invention.

Having thus described my invention, what I claim is:

1. In a traffic protection scheme in which a stretch of railway track is divided into two sections, the combination comprising, a track circuit for each of said sections each including the rails of its section and each supplied with current periodically varied according to a given code and each including a track relay which follows said given code, a contact of each of said track relays each repeatedly closed alternately in a first and a second position while its track relay is following said given code, a decoding transformer, means controlled by the contact of one of said track relays for repeatedly reversibly energizing the primary winding of said transformer, a code detecting relay, means controlled by the contact of the other track relay for rectifying current from the secondary winding of said transformer for energizing said code detecting relay, and signal controlling means controlled by said code detecting relay.

2. In a traffic protection scheme in which a stretch of railway track is divided into two sections, the combination comprising, a track circuit for each of said sections each including the rails of its section and each supplied with current periodically reversed at a given code rate and each including a polarized code following track relay, a decoding transformer, means controlled by a polar contact of one of said track relays for repeatedly reversibly energizing the primary winding of said transformer, a code detecting relay, means controlled by a polar contact of the other track relay for rectifying current from the secondary winding of said transformer for energizing said code detecting relay, and signal controlling means controlled by said code detecting relay.

3. In a traffic protection scheme in which a stretch of railway track is divided into two sec-

tions, the combination comprising, a track circuit for each of said sections each including the rails of its section and each supplied with current periodically interrupted at a given code rate and each including a code following track relay having a front and a back contact point, a decoding transformer, means controlled by the front and back contact points of one of said track relays for repeatedly reversibly energizing the primary winding of said transformer, a code detecting relay, means controlled by the front and back contact points of the other track relay for rectifying current from the secondary winding of said transformer for energizing said code detecting relay, and signal controlling means controlled by said code detecting relay.

4. In a traffic protection scheme in which a stretch of railway track is divided into two sections, the combination comprising, a track circuit for each of said sections each including the rails of its section and each supplied with current periodically varied according to a given code and also each including a track relay which follows said given code, a decoding transformer, means controlled by one of said relays for energizing the primary winding of said transformer, means controlled by the other of said relays for rectifying the current output from the secondary winding of said transformer, and traffic controlling means controlled by said rectified current.
